CLAIM

The ornamental design for a double-walled beverage container, as shown and described.

DESCRIPTION

FIG. 1 is a front perspective view of a first embodiment of a double-walled beverage container according to my design; FIG. 2 is a front elevation view of the first embodiment; the back elevation view of the first embodiment is a mirror image of FIG. 2 and therefore omitted;

FIG. 3 is a right side elevation view of the first embodiment; FIG. 4 is a left side elevation view of the first embodiment; FIG. 5 is a top plan view of the first embodiment;

FIG. 6 is a bottom plan view of the first embodiment; FIG. 7 is a front perspective view of a second embodiment of a double-walled beverage container according to my design; FIG. 8 is a front elevation view of the second embodiment; FIG. 9 is a back elevation view of the second embodiment; FIG. 10 is a right side elevation view of the second embodiment;

FIG. 11 is a left side elevation view of the second embodiment;

FIG. 12 is a top plan view of the second embodiment;

FIG. 13 is a bottom plan view of the second embodiment; FIG. 14 is a front perspective view of a third embodiment of a double-walled beverage container according to my design; FIG. 15 is a front elevation view of the third embodiment; the back elevation view of the third embodiment is a mirror image of FIG. 15 and therefore omitted;

FIG. 16 is a right side elevation view of the third embodiment;

FIG. 17 is a left side elevation view of the third embodiment; FIG. 18 is a top plan view of the third embodiment;

FIG. 19 is a bottom plan view of the third embodiment;

FIG. 20 is a front perspective view of a fourth embodiment of a double-walled beverage container according to my design;

FIG. 21 is a front elevation view of the fourth embodiment;

FIG. 22 is a back elevation view of the fourth embodiment;

FIG. 23 is a right side elevation view of the fourth embodiment;

FIG. 24 is a left side elevation view of the fourth embodiment;

FIG. 25 is a top plan view of the fourth embodiment; and,

FIG. 26 is a bottom plan view of the fourth embodiment.

The broken lines are for illustrative purposes only and form no part of the claimed design.
